UNITED STATES PATENT OFFICE.

HERMANN MERKEL, OF ST. LOUIS, MISSOURI.

DESIGN FOR A HYDROCARBON-BURNER.

SPECIFICATION forming part of Design No. 32,002, dated December 19, 1899.

Application filed November 22, 1899. Serial No. 737,956. Term of patent 7 years.

To all whom it may concern:

Be it known that I, HERMANN MERKEL, a citizen of the United States, residing in the city of St. Louis, State of Missouri, have invented and produced a new and original Design for a Hydrocarbon-Burner, of which the following is a specification.

Figure I is a side elevation of a hydrocarbon-burner embodying my new design. Fig. II is a plan.

As shown in the drawings, the leading or essential feature of my new design consists of the cylindrical portion 1, having rectangular recesses 2 in its outer face and the ribs 3 between the recesses 2 and having the vertical opening 4, extending downwardly through its center and forming a mixing-chamber, and the gas-openings 5, connecting the recesses 3 with the opening 4, the bead 6 at the lower end of the cylinder 1, the cylindrical portion

7, extending downwardly from the bead 6 and having the air-opening 8, the bead 9 at the lower end of the portion 7, the hemispherical portion 10, extending downwardly from the bead 9, the spherical portion 11, extending from the portion 10, the cylindrical portion 12, extending downwardly from the spherical portion 11, and the nipples 13 and 14, extending horizontally from opposite sides of the spherical portion 11. The lower end 15 of the portion 12 is screw-threaded, and the eye 16 extends downwardly from the nipple 13 and horizontally from the portion 12.

I claim—

The design for a hydrocarbon-burner substantially as herein shown and described.

HERMANN MERKEL.
